[57] CLAIM

An ornamental design for a table, as shown and described.

DESCRIPTION

FIG. 1 is a perspective view of a first embodiment of a table incorporating the inventive design;
FIG. 2 is a top view of the table of FIG. 1;
FIG. 3 is a front view of the table of FIG. 1. The rear view and the left and right side views are visually identical to the view shown in FIG. 3;
FIG. 4 is a bottom view of the table of FIG. 1; and,
FIG. 5 is a detail view to show the exterior contour of the rim of the table top.

FIG. 1

FIG.2

FIG.5

FIG. 3

FIG. 4
